(57) **CLAIM**

The ornamental design for a rongeur as shown and described herein.

DESCRIPTION

FIG. 1 is a top, rear, right perspective view of a rongeur, showing our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

In the drawings, the equal-length broken lines depict portions of the rongeur that form no part of the claimed design.

1 Claim, 5 Drawing Sheets
